UNITED STATES PATENT OFFICE.

GEORGE FREDERICK RABUS, OF CEDAR RAPIDS, IOWA.

PENCIL-PRINTING PRESS.

Application filed November 27, 1925. Serial No. 71,543.

This invention relates to the printing of pencils, such as are used for souvenir presentation and advertising purposes. The object of the invention is to produce a press 5 adapted for the rapid and automatic printing of pencils, more particularly hexagonal pencils, so as to produce a clean and perfect impression accurately disposed on the separate panels of the pencil.

10 The principal object of the invention is to produce a mechanism adapted automatically to select individual pencils from the supply magazine and to present them for printing with absolute accuracy and uniformity, whereby the printing lines are always disposed centrally and accurately on the respective panels of the pencils.

The invention is fully disclosed in the description and claims following, reference 20 being had to the accompanying drawings, in which:—

Fig. 1 is a side elevation of a printing press embodying the invention, as seen from the standpoint of the operator. Fig. 2 is a 25 fragmentary elevation from the opposite side of the machine, showing the mechanism for actuating the pencil delivering device. Fig. 3 is a similar view showing mechanism for actuating the pencil conveyor. Fig. 4 is 30 an elevation of the press as seen from the left end of Fig. 1. Fig. 5 is an elevation, similar in the main to Fig. 1, partly sectional, and showing the mechanism within the main frame as it would be seen with the 35 front side of the frame removed. Fig. 6 is a cross section of the press, mainly central to the pencil chuck, and as seen from the right of Fig. 1. Fig. 6^a is a detail view of the Geneva movement for the chucks, 40 taken in the plane of the line 6^a—6^a of Fig. 6, looking toward the left. Fig. 7 is a view in perspective, showing the mechanism for taking the pencil from its chucks and delivering it to the printing point. Fig. 8 is 45 a bird's-eye view, showing the mechanism that appears in Fig. 7 and also a device for holding the pencil securely at the printing point. Fig. 9 is a bird's-eye view of the platen and connected mechanism, partly in section. Fig. 10 is a view in perspective 50 illustrating an improved stool for supporting the rubber type used in this class of printing.

The machine as a whole includes many 55 features familiar in printing art, but in

order to a clear understanding of the press, and especially its novel features, the whole mechanism will be described briefly as follows:

In the drawing, 5 denotes the main frame, 60 composed of a pair of similar uprights suitably connected by crossbars 6, one of which appears in Fig. 4. Journaled in these uprights is the principal driving shaft 7 carrying a pulley 8 adapted for connection with an electric motor not shown. A pinion 9 engages a spur gear 10, acting as an idler, and to this is connected another pinion 11 meshing with a gear 12 forming a part of an assembly connecting with the main shaft 70 of the press 13. This shaft carries two main cams 14 and 15, and these transmit motion intermittently to rocker arms 16 and 17, respectively, for purposes which will be explained presently. At the top of the 75 main frame separate inking rolls 18 and 19 are mounted at opposite ends, and cooperate with distributing rolls 20 in a familiar way. In practice the operator applies a dab of ink directly to the large roll, and an automatic inking fountain is not actually necessary, though the same is supplied to the press as actually constructed, but not illustrated herein. It is to be understood that the separate inking devices are for the purposes of printing in separate colors, for 80 which the press is specially adapted. The large ink-rolls are driven by gears 12^a and idlers 12^b engaging the gear 12. 85

On a cross-shaft 21 is mounted rockably 90 the arm 16 carrying a roller 16^a engaging the cam 14. To the upper end of this arm is connected a pair of links 22 and 23. These engage levers 24 and 25, respectively, which are mounted on the respective cross-shafts 95 26 and 27. These levers, which are disposed on their carrying shafts in pairs, serve as supports for inking rolls 28 and 29, adapted to engage the ink distributing rolls at one extreme of movement, and to alternately ink 100 the type when carried to the other extreme.

At this point it may be said that while the apparatus herein described is adapted to perform its various functions, no special attempt has been made to show the mechanism in the exact positions necessary to the performance of said functions in due sequence. This of course is merely a matter of adjustment, and in considering the operations of the machine a description of the 110

sequence of operations is to be considered rather than the illustrations in the drawings.

- Between the two side frames is mounted 5 the platen bed-plate 30. This carries the sliding platen 31, to which a reciprocating motion is imparted by a sector gear 32 mounted rockably on the shaft 21, and engaging a rack 33 on the under side of the platen. The sector gear by segmental gear 34 connects with the arm 17 and this, by its roller 17^a, engages the cam 15. A continuous, but reciprocating motion, is thus imparted to the platen.
- 15 The special apparatus whereby a pencil A is brought into printing connection with the printing mechanism above described will now be set forth in detail.
- In the upper, central portion of the frame 20 is mounted a bearing yoke 35, which forms the inner bearings for pencil supporting spindles to be described presently. The out-board bearings 36 are carried in bracket arms 37 secured to the frame. Both the yoke and 25 out-board bearings are mounted to move a limited distance up and down, downward pressure being brought to bear upon the yoke by springs 38, for the purpose which will be described later. The support for 30 the outboard bearing is sufficiently flexible to allow for all the movement required at those points. The pencil-holding spindle assembly 35 comprises a group of units described as follows: Mounted slidably in the bearings are sleeves 39 carrying chuck plungers 40. These at their inner ends 40^a, are divided into six segments and are reduced at 40^b so as to render the chuck fingers slightly flexible. The chucks at 40^c have enlargements to 40 engage the constricted throats 39^a of the sleeves. As the chucks retreat outwardly the chuck fingers expand automatically, and the opposite movement tends to press them together so as to grasp the six sides of the 45 pencil as inserted in them. Movement in both directions is effected by means of large cam wheels 41 and 42 carried by the main shaft. The chuck spindles are provided with rollers 43 rotatable thereon which 50 rollers engage grooves in the cam wheels, as shown. By this means the chuck spindles are simultaneously withdrawn to admit the ends of the pencils between them, and are thrust inwardly to engage the pencil and to 55 grip it tightly at both ends. Each spindle is bored centrally from end to end and in the bore is mounted a stationary rod 44 carried at the outer end by the out-board bracket as described. These rods serve to 60 engage the ends of the pencil as the chucks are withdrawn, and prevent its being caught by either end when it is desired to drop the same. In the case of the clutch spindle which connects with the end of the pencil 65 carrying the rubber tip, the in and out mo-

tion is about double that of the other spindle, since it is necessary for the clutch to engage the body of the pencil at a point beyond the rubber tipped thimble. It is also desirable, in order to give proper support to 70 this chuck, that the sleeve should also travel inwardly with the chuck, but needs to move only about half the distance. This, as herein shown is effected by means of a separate roller 45 operating in a cam groove 45^a. 75 The various cam rollers are connected with collars which on their under sides rest on the curved surface of the cam wheels, and are thus prevented from turning. Within these collars the spindles and sleeves are free 80 to revolve. The sleeves and spindles are made to revolve concurrently. The revolution of the spindle is necessarily intermittent, so as to give time for other movements in the 85 operation of the press. To secure this intermittent movement the sleeves carry pinions 46, and these are adapted to engage interrupted gears 47 by means of a make-and-break gear connecting device 48, of the well known Geneva movement type. This 90 comprises a shoe concaved on one side so as to coincide with the periphery of the cam wheel. This periphery is broken at 49, opposite the teeth of the interrupted gear, so that when the shoe reaches this gap the gear may engage with the pinion and thus revolve the 95 spindle, in a familiar way.

A bridge 50 carried by the frame supports a hopper-like magazine 51 to carry a supply 100 of pencils disposed endwise therein. The lower opening of this hopper terminates in a pair of guide-ways 51^a at each end to carry the ends of the pencils as they move downwardly in single file. In this downward movement the row of pencils is arrested by 105 an escapement 52. This comprises a depending and swinging device embracing the guide-ways and provided at its inner sides with inwardly projecting teeth 52^a and 52^b disposed in opposite and staggered relation 110 to each other. It will be evident that in one position the tooth 52^a will catch and hold the row of pencils, and as the escapement swings to the opposite position this pencil will drop to the lower tooth 52^b, and thus 115 the pencils will be delivered singly and successively to the bottom of the guide-way. At this point they are caught by a cross-plate 52^c and between it and the other member of the guide-way the pencil may pass out laterally through a gap 52^d. As the pencil is moved in this direction each end engages a notch 52^e in the escapement, which serves to arrest its outward movement, and also serves, as the pencil moves laterally, to shift the 120 escapement to its opposite position.

The pencil is transferred from its position in the escapement to the final position for engagement with the clutches by a pair of grippers 53 attached to a rock-shaft 54, to 125

which a rocking movement is imparted from the rock-shaft 26 by short lever 55 connecting by a link 56 with another lever 57 attached to the rockshaft 54. In its backward movement the head of the gripper engages a roller 52^a and thus moves the escapement to the position shown in Fig. 7. As it moves in the opposite direction its beak engages the body of the pencil by its flat sides. This engagement is made effective for all sizes of pencils, the diameters of which vary considerably, by making one jaw of the gripper 53^a movable as indicated and providing it with a spring 53^b adapted to close the beak so as to grasp the smallest size of pencil. In practice the grasp of this beak on the pencil is always by its flat sides, so that when the pencil is finally delivered to the clutch spindles it is always in one position considered circumferentially. This position corresponds exactly with the position of the spindle at that time, so that the jaws of the clutches exactly coincide with the flat sides of the pencil. Once grasped by the clutch spindles the revolution of the pencil in the subsequent operation of printing will always be uniform, and this is exactly timed to correspond with the reciprocating movement of the platen in the act of printing. It will be evident therefore that by so adjusting the printing type that the type will be in accurate register with one pencil, it will also be in such register with all subsequent pencils and the printing line may be disposed on the respective panels of the pencil with the utmost nicety and precision.

As the pencil is deposited at the printing place and engaged by the respective clutches, a keeper 58 mounted on a rock-shaft 59 engages the upper side of the pencil and holds it securely, but elastically during the printing operation, at a point intermediate to the terminal clutches. The rock-shaft carrying this keeper is actuated intermittently by a cam 60 cooperating with a short lever 61 and a spring 62. The cam itself may be simply a ring forming a part of the cam wheel assembly above described with a gap therein shown in Fig. 8 to permit the rock-shaft 59 to carry the keeper to the holding position through the tension of the spring 62. As the cam engages the lever 61 the keeper is thrown to initial position, as will be evident. The rock-shaft itself is carried in bearings 35^a and 35^b of the yoke 35. A hole 5^a large enough to admit of a little play of the rock-shaft is formed in the main frame through which the rock-shaft passes. The main purpose of this keeper is to provide for the accurate positioning on the printing type of pencils which are not straight or are otherwise somewhat distorted. The tension of the spring is sufficient to correct these inequalities of the pencils and so insure plain and correct printing.

In the bed-plate which carries the platen is set a pair of racks 63, which are traversed by a corresponding pair of pinions 64 carried by a shaft 65 journaled in the platen, as best shown in Fig. 9. These pinions also engage a pair of rails 66, which are formed as racks on their under side. The rails are mounted slidably in guides 67 of the platen, and it will be evident that as the platen reciprocates these rails will be moved twice as far endwise as the platen. This allows for sufficient forward movement of the rails to enable them to carry the pencil when printed to the final discharging position. It will be understood that when printed the chucks release it and drop it as they retreat on the top of these rails and at a point in their retreating movement coinciding with shoulders 66^a near the delivery ends thereof. Referring to Fig. 5, it will be seen that this discharging position coincides with discharge plates 68 carried by the press frame and their inclined rearward faces are directed toward a pencil conveyor 69. A little up-standing shoulder 68^a on each of these catch-plates prevents the retreat of the pencil, which thence falls and slides to the conveyor. The latter comprises a pair of endless chains (one of which pair is shown) carried by sprockets 70 and 71, to which intermittent forward movement is imparted by means of a ratchet and pawl 72 actuated by a reciprocating lever 73 and a link 74.

Aside from their function of delivering the pencil from the printing position to the discharging position, these rails also serve the important purpose of supporting the pencil holding chucks at an accurate and determinate level regardless of the size of the pencil held by said chucks. It will be noted that the ends of the chucks rest on these rails (Figs. 5 and 9), and support them against the tension of the yoke-pressing springs. The object of this is to bring the printing face of the pencil always to a precise level with respect to the printing face of the type. If all pencils were exactly uniform, both in size and in the diameter of cross panels (that is to say, exactly symmetrical in section), it would not be necessary to move the chucks from a continuous position axially. This device takes care of these variations however, and insures that the printing face of the pencil shall always exactly coincide with the level of the type face, thus insuring clean, sharp and accurate printing impressions. The slight elasticity of the separate jaws of the chucks takes care of the irregularities in the diameters of different pencils, yielding vertically as the chuck-spindles roll over the supporting surfaces of the pencil carrying rails.

For printing in plural colors, for which the press is especially designed, the platen is provided with a pair of type-supporting

plates 75 supported by springs 76, one at each corner. Screws 77 extending through these plates and through the supports, permit any desired movement of the plates in order 5 to secure an exact leveling of the type carried thereby. The type itself is a strip of rubber type 78, and is best attached to its support by an adhesive. The main support of the type above the plates is a stool 79, best shown in Fig. 10, which is attached to the supporting plate by a clamp 80. To facilitate the adjustment of the type on its support, a removable plate is provided for the stool, as shown in Fig. 10. This comprises 10 a thin flat plate 81, provided with depending studs 82 seated in corresponding holes in the stools. The studs are held frictionally in position by the pressure of side springs 83 having contact therewith through holes 84 in the side of the stool. The plates are thus held frictionally in proper position, and are easily removable by the operator for attachment or adjustment of the type.

The pencils as disposed in the hopper-like magazine fall through the gap at the bottom 25 by gravity, and thence through their race-ways to the gripping position. To arrest any possible tendency of the pencils to clog in the magazine, the latter is provided with 30 agitators 84 carried by a rock-shaft 85, to which reciprocating movement is given by the rock-shaft which actuates the grippers, a short crank 86 and a connecting link 87. This keeps the pencils stirred sufficiently to 35 insure their dropping regularly into their final guide-ways in a regular and continuous series.

The operation of the press will be clear 40 from the foregoing description, the sequence of operations being as follows: As above described the platen moves back and forth continuously. In the course of this movement the type carried by the platen is inked by the respective inking rollers, which are depressed alternately to make the contact. When the type is in position to present the first line to the first printing surface 45 of the pencil, the pencil-carrying chuck-spindles begin to revolve exactly in unison with the movement of the platen. Prior to this movement the pencil grippers have rocked the escapements to release a single pencil, have 50 then moved the pencil to the printing position, and the pencil-holding finger intermediate of the chucks has moved to its position for holding the pencil in exact alignment during the printing operation. The revolution of the pencil holding spindles is 55 continued until the entire printing has been done in both colors, the platen moving toward the forward end of the press, which is at the left in Fig. 1. The pencil-carrying rails have then reached the point where they 60 may receive the pencil as dropped on their forward ends, at which point the chucks

cease to rotate and are withdrawn from the ends of the pencil. A reverse motion of the plate carries the pencil to its discharge position, where it is received by the conveyor.

Having thus described my invention, I 70 claim—

1. In a pencil printing press, a movable platen to carry the type, inking means therefor, endwise movable chucks, adapted to rotate intermittently in time with the platen 75 movement, a pencil supplying magazine, means adapted to transfer a pencil from the magazine to the printing position, and actuating means for operating the said mechanisms.

2. In a pencil printing press, a pencil magazine provided with means for single delivery of pencils, means adapted to transfer the single pencil from the magazine to the printing position, endwise movable, intermittently rotating chucks to hold the pencil positively with respect to its printing faces, and a platen carrying the printing type and moving in unison with the revolution of the pencil.

3. In a pencil printing press, having actuating mechanism substantially as described, a continuously moving type carrying platen, a pencil magazine adapted for delivery 95 of pencils in a row, means for transferring a single pencil from the magazine to the printing position, chucks adapted to receive the ends of the pencil at such position and hold it positively, and movable in and out of the path of the pencil as transferred.

4. In a pencil printing press, a continuously moving platen, a pencil holding magazine, an escapement therefor adapted to deliver the pencils singly, grippers adapted to hold the 105 pencil by its flat sides and transfer it to the printing position from the magazine, and chucks positioned normally in register with the pencil as delivered to the printing position, and means adapted to rotate the chucks 110 in unison with the movement of the platen.

5. In a pencil printing press, a movable platen, a pencil-holding magazine, an escapement therefor adapted to deliver the pencils singly, rocking grippers adapted to move 115 the escapement to and fro and carry the pencil by its flat sides to printing position, chucks movable in and out of the path of the pencil, and normally in register with the pencil at its printing position, and means 120 adapted to rotate the pencil in unison with the movement of the platen.

6. In a pencil printing press, a movable platen, pencil holding chucks, intermittently rotatable, a pencil-holding magazine, grippers adapted to transfer a single pencil therefrom to printing position, and an intermediate disposed finger adapted to hold the pencil in printing alignment.

7. In a pencil printing press, a movable

5 platen, pencil holding chucks, intermittently rotatable, a pencil-holding magazine, grippers adapted to transfer a single pencil therefrom to printing position, and an interposed finger adapted to hold the pencil elastically in printing alignment.

8. In a pencil printing press, a movable platen, a pencil-holding magazine, grippers adapted to engage a single pencil by its flat 10 sides elastically and transfer it to printing position, chucks to hold the pencil in positive rotative printing position with respect to the type face, and means to actuate said chucks intermittently.

13. 9. A pencil printing press provided with chuck having elastic gripping jaws adapted to engage the flat sides of the pencil, and a movable platen having rails adapted to carry said jaws at a definite level with respect to 20 the type face.

10. A pencil printing press provided with pencil gripping clutches, bearings therefor adapted to move to and fro with respect to the printing level, a platen movable across 25 the pencil as carried by the clutches, and rails movable on said platen as adapted to carry the ends of the clutches, whereby the side of the pencil to be printed is presented to the type face at a definite and uniform 30 level.

11. A printing press for pencils having chucks movable elastically with respect to the printing level, a platen movable trans-

versely thereof, and rails carried by said platen and carrying the pencil-holding ends 35 of the chucks, the jaws of the chucks being elastic, whereby the face of the pencil exposed to the type face is held at a definite level regardless of inequalities in the pencil sectionally.

12. A pencil printing press having intermittently rotating pencil holding chucks, a sleeve for the tip end holding chuck, end-thrust cams adapted to move the chuck and sleeves separately endwise, a movable platen, 40 and cooperating printing mechanism.

13. In a pencil printing press, pencil-holding chucks adapted to engage and disengage the ends of the pencil, and centrally disposed stops adapted to engage the ends of 50 the pencil as the chucks retreat.

14. In a pencil printing press, pencil-holding means, a movable platen for operating therewith, rails carried by the platen and movable thereon, said rails being adapted to carry the printed pencil from the printing position and deliver it to a discharging 55 position.

15. A pencil printing press having pencil holding chucks, a pencil conveyor, a platen 60 movable crosswise of the chucks, and pencil carrying rails movable on said platen, to deliver the printed pencil to said conveyor.

In testimony whereof I affix my signature.

GEORGE FREDERICK RABUS.
